UNITED STATES PATENT OFFICE.

BYRON A. WALKER, OF ERIE, PENNSYLVANIA, ASSIGNOR TO LOVELL MANUFACTURING COMPANY, OF ERIE, PENNSYLVANIA, A CORPORATION OF PENNSYLVANIA.

WRINGER.

Application filed July 21, 1921. Serial No. 486,362.

To all whom it may concern:

Be it known that I, BYRON A. WALKER, a citizen of the United States, residing at Erie, in the county of Erie and State of Pennsylvania, have invented new and useful Improvements in Wringers, of which the following is a specification.

Clothes wringers have been formed of wood frames and with metal frames. In some respects the wood frames are more desirable than the metal frames as screws hold in the wood much better than in metal, the slight elasticity of the wood adding to this effect. It is also much simpler to attach the wood frame wringer to the various wringer supports as they are found on modern washing machines as practically every washing machine has a variation in the support which variation must be met by the wringer structure. On the other hand the metal wringer corresponds more nearly in appearance and structure to the general structure of the power washing machines particularly and is stronger and more resistant to certain features of use than the all wood frame wringer. In the present invention I have combined the two materials retaining the desirable features of both. It also permits of the forming of the wooden portion of the wringer in a very much simpler and efficient manner.

The invention is illustrated in the accompanying drawings as follows:—

Fig. 1 shows a front elevation of the wringer.

Fig. 2 a side elevation.

Fig. 3 a top view of one of the stiles with a bearing in place.

Fig. 4 a longitudinal vertical section on the lines 4—4 in Figs. 2 and 3 through the center of the wringer.

Fig. 5 a cross section on the lines 5—5 in Figs. 1 and 3.

Fig. 6 a cross section on the lines 6—6 in Figs. 2 and 4.

1—1 mark the stiles. These stiles are formed with wooden insides formed with a block 2 at the bottom which is nearly the full width of the stile and the uprights 3 projecting in a line with the outer faces of the block 2 and forming between them the vertical guide groove 4. This simplifies the construction materially from that commonly used in wood wringers in which the part 2 must be made integral with the parts 3, and

the cutting of the slot wasting the material of the slot and at the same time offering some difficulty in producing a uniform product. Arranged in the insides at the opposite sides of the slot are guide grooves 5 in 60 which are arranged the bearings 6. Shafts 7 are journaled in the bearings and these carry the rolls 8 in the usual manner. Intermeshing gears 7^a are mounted on the shafts so as to drive one roll from the other. 65 Pressure springs 9 rest on plates 10, the plates resting on the upper bearings 6. Screw plates 11 rest on the upper ends of the spring and tension screws 12 operate on these plates, the tension screws being carried 70 by the top bar 13. A bracket 14 bridges the space across the top of the slot 4 and is secured to the side walls of the stiles by screws 15 which extend into the wooden insides. The bracket has a lip 16 on its upper edge 75 under which the top bar 13 extends. The top bar is formed of two parts 17 hinged at 18 and having the abutting ends 19. A shoulder 20 is caught by the latch 21 holding the bar normally in its rigid position but 80 upon the release of the latch releases the top bar so as to release the rolls in the manner described in the patent to N. B. Hutton, #1,139,122, May 11, 1915. The general structure so far described is similar to 85 wringers already made.

I provide a sheathing 22 for the stiles. The sheathing is preferably in the form of channels, one channel at the front and one at the back of each stile, the flanges of the 90 channel overlapping the inside and outside edges of the stiles. This sheathing is secured to the stiles by screws 23 at the top and by the screws 24 at the bottom, the screws 24 overlapping so as to prevent the 95 splitting of the block 3 between the slot 4 and the slot 25 and the slot 25 in place thereof adapts the bottom of the stile to a wringer support as 26. I prefer to carry the channels across the top at 27 so as to 100 house the top of the stiles as well as the sides. It will be noted that these channels splice the guide strips 3 and the block 2 holding the guide strips rigidly in relation to the block 2 and consequently giving to 105 the guide groove which may be formed in the side strips a perfect alinement and ample rigidity for wringer purposes. The side strips being formed in what is commonly known as a sticker can be made very accu- 110

rately so that the guide grooves can be given a closer and smoother fit than is practical where these guide grooves are formed in a wooden stile in which the two strips are integral with the bottom block. It will be noted that the screws 15 of the bracket 14 not only extend through the bracket but also through the metal sheath into the wooden inside. In this way the brackets may be very 10 economically and very securely mounted.

Connecting plates 28 extend from stile to stile, the screws 29 extending through these connecting plates, through the sheathing or metal re-enforcements of the wooden inside 15 into the wooden inside itself, the resilience of the wood yielding under pressure of the screw thus assuring a spring-pressed clamping engagement between the plates and the end stiles.

20 Guide plates 30 are arranged opposite the rolls and are secured to the end stiles by screws 31 which extend through the plates and the sheathing or re-enforcing channel plates of the stiles into the wooden insides thus making a secure union of these parts.

A guard plate 32 is arranged over the gears 7^a secured to the end stiles by the screws 33 which extend through the sheathing into the wooden insides and the screw 34 which extends through the guard plate directly into the wooden inside.

30 A screw 35 extends through the wooden inside between the sheathing plates and has a projecting end 36 which extends into a 35 slot 37 of the drain board.

The end stiles are clamped by a bolt 39 on a wringer support, the wood inside permitting of a convenient forming of the wringer and adapted to the support and 40 also springing slightly to assure a perfect engagement of the wringer with the support.

With this structure the wringer in appearance is a complete metal wringer. The 45 connecting parts are united by wood screws with the superior holding quality over metal to metal holding. The guide ways for the bearings are formed in wood and thus in a convenient manner house the springs and 50 bearings. The guide-ways are more accurate and uniform than is practical where the slots are cut out from an integral piece of wood and there is a considerable saving of material. The metal sheathing splices 55 the wood parts and thus makes possible the formation of the guide strips and bottom

block in separate pieces and at the same time protects that part of the wood which is most exposed from the direct action of water and thus prolongs the life of the 60 wringer. Further the shapes of the guide ways may be varied as the bearings vary or spring constructions vary so that in a very simple way the structure lends itself to the varying connecting parts of the 65 wringer.

It will also be noted that the sheathing forms a facing for the ends of the securing bolt 39. In the operation of the wringer this bolt is under considerable strain and the facing on the wood helps in sustaining this strain and at the same time the elasticity of the wood assists in maintaining a firm engagement.

What I claim as new is:-

1. A wringer stile formed with a wooden inside having a bearing slot therein, and a metal sheath forming a housing for the front and rear walls of the wooden inside said sheath extending from the top to the 80 bottom of said stile.

2. In a wringer, the combination of end stiles having wooden insides and metal sheaths forming housings for the insides; connecting plates between the stiles; and means extending through the plates and the metal sheaths into the wooden insides securing the plates to the stiles.

3. In a wringer, the combination of end stiles having wooden insides provided with bearing slots extending from the top thereof and metal sheaths forming housings for the insides; brackets bridging the tops of the slots; and means extending through the brackets and the sheaths into the wooden insides for securing the brackets to the stiles.

4. A wringer stile formed with a wooden inside comprising a bottom block and upwardly extending guide strips formed separately from the wooden block; and rigid metal plates splicing the block and strips.

5. A wringer stile formed of a wooden inside comprising guide strips projecting upwardly from a supporting block forming a guide slot between the strips; and a metal sheath comprising channels placed over the front and rear walls of the wooden inside, said channels splicing the block and strips.

In testimony whereof I have hereunto set my hand.

BYRON A. WALKER.
